DOUGLAS DUVAL CORNING, OF LYNN, MASSACHUSETTS.

AUTOMATIC MATERIAL-DISPENSING DEVICE.

1,345,350.

Specification of Letters Patent.

Patented July 6, 1920.

Application filed June 21, 1916. Serial No. 105,054.

To all whom it may concern:

Be it known that I, DOUGLAS D. CORNING, a citizen of the United States, residing at 58 Hamilton avenue, Lynn, in the county 5 of Essex and State of Massachusetts, have invented an Automatic Material-Dispensing Device, of which the following is a specification.

This invention relates to automatic material dispensing apparatus and has for its 10 object to provide a simple inexpensive and reliable device for automatically dispensing dry materials such as grain or other stock feed.

Figure 1 is a front elevation of dispensing apparatus in accordance with my invention.

Fig. 2 is a partial side view thereof as seen from the right of Fig. 1.

Fig. 3 is a rear view of the alarm clock, 20 removed, and

Figs. 4 and 5 are detail views illustrating the operation of the automatic valve release mechanism.

In Fig. 1, the cylindrical galvanized iron 25 receptacle (1) is provided with cover (2) and with bail (3) whereby the dispenser must be suspended for operation. The bottom of the container (4) is funnel shaped, the opening (5) at the base of which passes 30 into a uniform cylindrical chute (6) the lower opening of which (7) is either caused to be shut or open by the conical disk valve (8) being in its elevated (9) or lowered position (10) as the case may be. The conical 35 disk valve (8) is rigidly suspended by two supporting rods (11) which are free to slide vertically through guides or eyes (12) which are attached to chute (6). The upper ends of the supporting rods (11) are bent at 40 right angles (13) so that when conical disk (8) drops from its elevated position (9) to its lowered position (10), these arms (13) strike eyes (12' and 12'') and thus prevent disk (8) from dropping farther than the 45 required position (10). Furthermore arm (13') passes through the slit (14) in a gravity operating releaser here shown as a plate (15) which revolves about axis (16). Plate (15) is provided with a notch (17) into 50 which tongue (18) of latch (19) passes. Latch (19), which rotates about axis (20), is provided with an arm (21) which is set at right angles to the face of the latch (19).

A metal frame (22) is firmly attached to 55 cylindrical chute (6) by means of any suit-

able bracket (23). This metal frame (22) is provided with slits (24) and (25), so arranged as to allow the legs (26) and hanging ring (27) of alarm clock to be freely inserted to or withdrawn from the required 60 position in frame (22). Furthermore, the back of the frame (22) is provided with a dust shield (28) which extends upward as far as (29). The alarm clock is somewhat 65 altered to suit the special use.

After the alarm spring has been fully wound up, an alarm winding key (30) to which an extended arm (31) is attached, is screwed into position, the alarm setting thumb piece (32) is reapplied to its position and thus, because of its location on the 70 clock, allows a $\frac{1}{6}$ revolution to arm (31) when alarm device is released. To reset the alarm clock, the alarm setting thumb piece (32) is set to the required time for action 75 and the winding key (30) is given a clockwise $\frac{1}{6}$ turn from position (33) to position (34).

When the clock is set as above described, the action of the dispenser is as follows:—If 80 the cone (8) be in its lowered position (10) this is elevated to position (9) by a push upward with the hand. This elevating movement by means of the attached rods (11) in turn rotates the plate (15) clockwise to a position whereat the tongue (18) of the latch (19) engages itself, by means of gravity into notch (17). The alarm clock is inserted face outward into the frame (22), this brings arm (31) into correct position. Material is then placed into receptacle (1). When the time set arrives, the 85 arm (31) rotates a $\frac{1}{6}$ turn in a counter clockwise movement. In so doing, it strikes the arm (21) pushing it upward and thus 90 lowers the tongue (18) and disengages same from notch (17). Thus plate (15) is allowed to rotate about $\frac{1}{6}$ of a turn downward causing through supporting rods (11), the 95 conical disk (8) to drop to its lowered position (10) and in so doing the material from the chute (6) and the receptacle (1) flows 100 freely out through lower opening (7). The material by falling upon conical disk (8) is thereby spread out over the ground below. 105 In order that the material may also be distributed directly below the dispenser, two small openings (35) are cut out of disk (8) and fins (36) are attached at lower edge of 110 openings (35), these being at right angles

to disk surface, to arrest some of the grain and cause same to fall directly below dispenser.

I claim:

- 5 1. In combination with a receptacle having a discharge opening, a valve controlling said opening, a rod slidably mounted relative to said receptacle and carrying said valve, a pivoted plate adapted to be releasably engaged with said slidable rod, and a support pivoted below said plate and having a supporting and a non-supporting relation thereto.
- 10 2. In combination with a receptacle having a discharge opening, a valve controlling said opening, a rod slidably mounted relative to said receptacle and carrying said valve, a pivoted plate adapted to be releasably engaged with said slidable rod, a support pivoted below said plate and having a supporting and a non-supporting relation thereto, and a guide for said slidable rod adapted to limit the movement thereof in one direction.
- 15 3. In combination with a receptacle having a discharge opening, a valve controlling said opening, a rod slidably mounted relative to said receptacle and carrying said valve, a pivoted plate adapted to be releasably engaged with said slidable rod, a support pivoted below said plate and having a supporting and a non-supporting relation thereto, and a guide for said slidable rod, and a stop carried by said slidable rod and

adapted to contact said guide in the movement of said rod in one direction to thereby limit said movement.

4. In combination with a receptacle having a discharge opening, a valve controlling said opening, a vertically disposed gravity operating rod slidably mounted relative to said receptacle, and carrying said valve, a pair of aligned guide eyes on said container for guiding said rod, said rod having its upper end bent and constituting a stop adapted to contact the upper eye of said pair of guide eyes to limit the downward movement of the rod, a releaser adapted to engage said bent end and retain the rod in raised position, and means for actuating said releaser.

5. In combination with a receptacle having a discharge opening, a valve controlling said opening, a vertically disposed gravity operating rod slidably mounted relative to said receptacle, and carrying said valve, a pair of aligned guide eyes on said container for guiding said rod, said rod having its upper end bent and constituting a stop adapted to contact the upper eye of said pair of guide eyes to limit the downward movement of the rod, a pivoted plate having a slot to releasably receive the bent end of said rod and having a peripheral locking notch below said slot, and a latch pivoted below said plate and having a tongue adapted to lie in said notch.

DOUGLAS DUVAL CORNING.
